CLAIM

We claim the ornamental design for a transaction device, as shown and described.

DESCRIPTION

FIG. 1 depicts a perspective view of a front face of a transaction device.

FIG. 2 depicts a front elevational view of FIG. 1.

FIG. 3 depicts a back elevational view of FIG. 1.

FIG. 4 depicts a side elevational view of FIG. 1.

FIG. 5 depicts an opposite side elevational view of FIG. 1.

FIG. 6 depicts a bottom plan view of FIG. 1; and,

FIG. 7 depicts an top plan view of FIG. 1.

The broken lines in the drawings illustrate environmental structure on the article and form no part of the claimed design.
